UNITED STATES PATENT OFFICE.

EDWIN KELSEY, OF CALVERT, KANSAS.

GATE.

SPECIFICATION forming part of Letters Patent No. 408,628, dated August 6, 1889.

Application filed April 22, 1889. Serial No. 308,102. (No model.)

To all whom it may concern:

Be it known that I, EDWIN KELSEY, a citizen of the United States, residing at Calvert, in the county of Norton and State of Kansas, 5 have invented certain new and useful Improvements in Wire Gates; and I do declare the following to be a full, clear, and exact description of the invention, such as will enable others skilled in the art to which it app- 10 pertains to make and use the same, reference being had to the accompanying drawings, and to the letters and figures of reference marked thereon, which form a part of this specification.

15 This invention relates to wire gates composed of longitudinal wires or cables that are connected at their inner ends by eyebolts or otherwise to the gate-post, and have an end batten connecting the outer ends of the said 20 wires or cables.

The object of the invention is to improve the general construction of this class of gates and devise a means whereby the wires or cables can be drawn taut by simply pressing 25 down on the end batten.

The improvement consists of the novel features which will be hereinafter more fully described and claimed, and shown in the annexed drawings, in which—

30 Figure 1 is a front view of a gate embodying my invention, showing the operation of same by dotted lines. Fig. 2 is a detail cross-section of one end of the gate, on the line X X of Fig. 1. Fig. 3 is a cross-section of one 35 end of the gate, on the line Y Y of Fig. 1; and Fig. 4 is a side view of the post, parts being broken away, and shows the operation of the latch by dotted lines.

A and B represent the posts at each side of 40 the gateway, respectively.

C represents the longitudinal wires or cables that compose the gate, which are connected at their inner ends to the post A by suitable devices, as the eyebolt d. The batten D is connected to the outer ends of the wires or cables C, and the brace E, extending obliquely across the gate, is pivotally connected at its outer end to the batten D and is hinged at its inner end to the post A. 45

50 The brace F strengthens the connection between the brace E and the batten D.

The latch G is fastened at its lower end to the post B, and its upper end q is bent at right angles and extends through an opening b in the post B. The stop H on the bat- 55 ten is provided with two arms h h, which embrace the sides of the latch G, and is adapted to be engaged by the said latch G. The keeper I at the base of the post B is designed to embrace the foot of the batten D and hold 60 said batten against the tension of the wire or cables C.

The operation of the gate is as follows: When the latch G is released from the stop H, the batten D will rise sufficiently to dis- 65 engage itself from the keeper I, and the gate can be swung open from either side. When the gate is closed, it is fastened by depress- 70 ing the batten D, which effects an engage- ment of said batten with the keeper and causes the stop H and latch G to engage. The depressing of the batten D effects a ten- 75 sion on the wires or cables C by bringing the oblique brace E nearer a horizontal line. Obviously when the latch G is released from 80 the stop H the said wires or cables will slacken and cause an elevation of the said batten, as hereinbefore set forth, and as shown by dotted lines in Fig. 1. The latch is adapted to spring away from post B at its up- 85 per end, and is provided with the hook g', which overlaps the stop H when the batten D is depressed and holds the latter down. To disengage the latch G from the stop H, press outwardly and downwardly on its bent end q, (shown most clearly in Fig. 4,) when the de- 90 sired result will be effected.

Having thus described my invention, what I claim, and desire to secure by Letters Patent, is—

1. The combination, with the post A, the batten D, the wire C, connecting the post A and batten D, and the oblique brace E, ex- 95 tending from the post A to batten D and adapted to swing horizontally and vertically, of the stop H on batten D, having arms h h, the post B, and the latch G, having the hook g' to engage with the stop H, and having the bent end q, substantially as and for the pur- 100 pose described.

2. The combination of the posts A and B, the batten D, the wires C, connecting the post

A and the batten D, the oblique brace E, extending from post A to batten D and adapted to swing horizontally and vertically, the stop H, having arms $h\ h$, the latch G, having the hook g' , and having the bent end g , and the keeper I, secured to the post B and adapted to embrace the foot of the batten D, substantially as and for the purpose described.

In testimony whereof I affix my signature in presence of two witnesses.

EDWIN KELSEY.
